UNITED STATES PATENT OFFICE.

HERMAN WATERMAN, OF NEW YORK, N. Y.

DESIGN FOR A STOVE-TOP PLATE.

43,917.

Specification for Design.

Patented Apr. 22, 1913.

Application filed January 10, 1913. Serial No. 741,337. Term of patent 7 years.

To all whom it may concern:

Be it known that I, HERMAN WATERMAN, a citizen of the United States of America, residing at New York city, Manhattan borough, county and State of New York, have invented a new, original, and ornamental Design for a Stove-Top Plate, of which the following is a specification, reference being had to the accompanying drawing, forming part hereof, which represents a plan view of a stove-top plate, showing my new design.

I claim:

The ornamental design for a stove top-plate, as shown.

Signed at New York city, New York, this 8th day of January, nineteen hundred and thirteen.

HERMAN WATERMAN.

Witnesses:

EDWARD A. JARVIS,
MAURICE BLOCK.
